MAX HARTENHEIM, OF PITTSBURGH, PENNSYLVANIA, ASSIGNOR TO WESTINGHOUSE ELECTRIC AND MANUFACTURING COMPANY, A CORPORATION OF PENNSYLVANIA.

RELAY.

1,227,433.

Specification of Letters Patent. Patented May 22, 1917.

Application filed August 10, 1915. Serial No. 44,743

To all whom it may concern:

Be it known that I, MAX HARTENHEIM, a subject of the German Empire, and a resident of Pittsburgh, in the county of Allegheny and State of Pennsylvania, have invented a new and useful Improvement in Relays, of which the following is a specification.

My invention relates to relays and particularly to hot-wire relays that are utilized for controlling the operation of dynamo-electric machines.

One object of my invention is to provide a relay of the above indicated character that operates to effect engagement of its contact members when the current traversing the relay is decreasing and of a predetermined value.

Another object of my invention is to provide a relay that will operate to effect engagement of its contact members when a predetermined current traverses the same for a predetermined time.

In the starting of dynamo-electric machines as motors, it is desirable to insert a resistor in series with the armature thereof to limit the amount of current that flows when the circuit is first closed. This current rises to a maximum value and then decreases when the counter electromotive force gradually builds up, and, when it has decreased to a predetermined value, the resistor is usually short-circuited. If an ordinary relay is used for controlling the short-circuiting of the resistor, it will operate when the current reaches a predetermined value while ascending. Since this does not permit the motor to accelerate properly before the resistor is short-circuited, I provide a relay that automatically controls the short-circuiting of the resistor when the accelerating current is decreasing and of a predetermined value.

I further provide means whereby the relay hereinbefore set forth may be utilized for interrupting the circuit of the motor if a predetermined load traverses the same for a predetermined time.

Figure 1 of the accompanying drawings is a diagrammatic view of a relay embodying my invention, Fig. 2 is a diagram illustrating the starting current of a dynamo-electric machine, and Fig. 3 is a diagrammatic view of a modified form of a relay embodying my invention.

In Fig. 1 of the drawings, an electric circuit 1, comprising two conductors 2 and 3, is provided for supplying a motor 4 with current. A resistor 5 is so connected to the armature of the motor 4 that, when the same is started, the rush of current that traverses the armature is limited until the motor has accelerated a sufficient amount. The resistor 5 is connected, at one terminal, to one terminal of the armature of the motor 4, and at its other terminal, to one terminal 6 of a relay 7. The other terminal 8 of the relay 7 is connected to the conductor 3. A conductor 9 is also connected to the terminal 8 and to a stationary contact member 10. A conductor 11 is connected to a stationary contact member 12 and also to one terminal of the resistor 5 so as to provide a short-circuit path for the current traversing the armature of the motor 4 when it is desirable that the resistor 5 and relay 7 be disconnected from the circuit.

The relay 7 comprises two parallel-connected conductors 13 and 14 that are connected, at their respective ends, to the terminals 6 and 8. Two arms 15 and 16 are pivotally mounted upon stationary members 17 and 18, respectively. Contact members 19 and 20 are mounted at the respective ends of the arms 15 and 16 and are adapted to engage stationary contact members 21 and 22, respectively. The two conductors 13 and 14 are maintained under tension by means of two connectors or cords 23 and 27 and springs 25 and 29. The arm 15 is connected, by the cord 23, to the mid point 24 of the conductor 14 and also to one end of the spring 25, the other end of which is connected to a stationary member 26. Likewise, the arm 16 is connected, by the cord 27, to the mid point 28 of the conductor 13 and also to one end of the spring 29, the other end of which is connected to a stationary member 30. The springs 25 and 29 are so adjusted that the contact members 19 and 21 are normally in engagement when no current traverses the conductors 13 and 14, and the contact members 20 and 22 are normally out of engagement when no current traverses the conductors 13 and 14. The stationary contact member 21 is connected to one terminal of the winding 31 of the relay 32, the other terminal of which is connected to the conductor 2. The relay 32

comprises a movable core member 33, two movable contact members 34 and 36 and a restraining spring 35. The stationary contact member 22 is connected to the conductor 8, and the arms 15 and 16 are electrically connected together by a conductor 37.

The conductors 13 and 14 are of relatively different cross-sectional areas and have, therefore, different thermic inertia. However, it is advisable that they be constructed of such materials that the currents traversing the same are substantially equal. It will be understood that the conductor 13 having the greater thermic inertia expands more slowly than the conductor 14, since it is of relatively larger cross-sectional area.

When current traverses the circuit 1, a rush of current traverses the armature of the motor 4, the resistor 5 and the conductors 13 and 14. The contact members 19 and 21, on account of the substantially instantaneous heating of the conductor 14, quickly separate while the contact member 20 slowly approaches engagement with the contact member 22. After the current has reached its maximum value, it begins to decrease, and the conductor 14 contracts, while the conductor 13 is still expanded sufficiently to maintain the contact members 20 and 22 in engagement. Thus, the contact members 19 and 21 are again engaged, while the contact members 20 and 22 are still engaged to thus complete the circuit through the winding 31 of the relay 32, causing the movable contact member 34 to engage the stationary contact members 10 and 12, whereby the current that traverses the armature of the motor 4 is permitted to traverse the conductors 9 and 11 to thus short-circuit the resistor 5 and the relay 7.

A conductor 38 is connected to one terminal of the winding 31 and to a stationary contact member 39. A conductor 40 is connected to the corresponding stationary contact member 41 and to the stationary contact member 22. This connection is provided so that, when the relay 32 operates, the movable contact member 36 engages the contact members 39 and 41 to thus maintain the relay 32 in operative relation when the conductors 13 and 14 contract to disengage the contact members 20 and 22 after the relay 7 has been short-circuited.

It will be seen from the above description that the current traversing the armature of the motor 4 follows substantially the curve shown in Fig. 2, wherein the line 37 represents the value of the current for which the relay 7 is adjusted. The point 38 indicates the point at which the contact members are simultaneously in engagement. Although the point 39 indicates the same value of current as the point 38, the relay 31 will not be actuated at the point 39 because the contact members are only simultaneously en-

gaged when the current is decreasing and of a predetermined value.

In Fig. 3 of the drawings the relay 31 is adapted to short-circuit the resistor 5 only, and a stationary contact member 42 is adapted to be engaged by the movable contact member 19 under predetermined conditions. A circuit interrupter 43, having a trip coil 44, is connected in circuit with the motor 4, and the trip coil 44 is connected to the conductor 2 and to the contact member 42.

Upon starting the motor 4, the relay 7 operates when the current is decreasing and of a predetermined value to short-circuit the resistor 5 only. If, however, an excess current again traverses the windings of the motor 4 and persists for a time that is sufficient to cause the conductor 14 to expand again, the contact member 19 will engage the contact member 42 to thereby trip the circuit interrupter 43, thus providing ample protection against overloads as well as means for automatically short-circuiting the starting resistor.

If the potential of the circuit 1 is reduced to a predetermined value, the winding 31 will be sufficiently deenergized to permit the spring 35 to open the short-circuit path around the resistor 5 to thus prevent the motor from being injured when the potential is again raised.

While I have described my invention with respect to a particular direct-current application, it will be understood that I do not limit my invention to that particular application or to the particular construction illustrated, as many modifications may be made therein without departing from the spirit and scope of the invention as set forth in the appended claims.

I claim as my invention:

1. A relay comprising two thermal-responsive members adapted to be heated equally and to have different thermal inertia, contact devices adapted to be actuated by the movement of the said thermal-responsive members, one of said contact devices being adapted to be normally open and the other to be normally closed.

2. A relay for an electric circuit comprising two conductors, stationary contact members, and movable contact members adapted to be actuated by the expansion and contraction of the conductors when currents traverse the same, the time of expansion and contraction of one of the conductors being so different from that of the other that the contact members are adapted to be engaged simultaneously only when the current traversing the conductors is decreasing and of a predetermined value.

3. A relay comprising two parallel-connected conductors of different cross-sectional areas, stationary contact members,

- and movable contact members operatively connected to the parallel-connected conductors, the contact member that is connected to the conductor having the smaller cross-sectional area being normally in engagement with its stationary contact member and the other contact members being normally disengaged, the first-mentioned contact member being adapted to operate relatively more quickly than the other contact member.
4. A relay comprising two conductors having relatively different cross-sectional areas, contact devices adapted to be actuated by the expansion and contraction of the conductors, the contact device that is actuated by the conductor having the smaller cross-sectional area being normally closed and the other being normally open.
5. A relay comprising two conductors having different thermal inertia, a normally open contact device adapted to be actuated by the movement of one conductor when current traverses the same, and a normally closed contact device adapted to be actuated by the movement of the other conductor when current traverses the same, the relative movements of the said conductors, when traversed by equal currents, being such that the contact devices are simultaneously closed only when the current traversing the conductors is a predetermined value and decreasing.
6. A relay for an electric circuit comprising two conductors having different thermal inertia, a normally open contact device adapted to be actuated by the relatively quick-responding conductor and a normally closed contact device adapted to be actuated by the relatively slow-responding conductor.
7. A relay comprising two conductors having substantially different thermal inertia, a plurality of movable contact members operatively connected to the conductors, and a plurality of stationary contact members adapted to be engaged by the movable contact members, one pair of contact members being adapted to be engaged simultaneously only when the current traversing the conductors is of a predetermined value and decreasing and the other pair being adapted to be engaged only when a predetermined current traverses the conductors for a predetermined time.
8. A relay comprising two conductors having different thermal inertia, coöperating contact members operatively connected to the conductors, said conductors being adapted to expand and contract when current traverses the same to cause the coöperating contact members to be engaged simultaneously only when the current traversing the
- conductors is a predetermined value and decreasing.
9. A relay comprising two thermal-responsive members, coöperating contact members actuated thereby, said responsive members having such thermal inertia that the contact members are adapted to be engaged simultaneously only under predetermined conditions.
10. A relay comprising two thermal-responsive members, coöperating contact members actuated thereby, said responsive members having such thermal inertia that the contact members are adapted to be engaged simultaneously only when the responsive members have been heated a predetermined amount and the amount of heating is being reduced.
11. In an electric circuit, the combination with two expandible conductors adapted to have different thermal inertia, of a normally closed contact device actuated by the movement of one conductor, and a normally open contact device actuated by the movement of the other conductor, the difference in thermal inertia of the said conductors being such that the contact devices are simultaneously closed only under predetermined conditions.
12. In an electric circuit, the combination with two thermal-responsive devices responsive in different degrees to current traversing the circuit, of contact members actuated by the movement of the said responsive devices, said responsive devices being adapted to so actuate the contact members that they are engaged and disengaged under predetermined conditions in the circuit.
13. In an electric circuit, the combination with two thermal-responsive devices responsive in different degrees to current traversing the circuit, of contact members actuated by the movement of the said responsive devices, said responsive devices being adapted to so actuate the contact members that they are engaged simultaneously only when the current traversing the circuit is decreasing.
14. In an electric circuit, the combination with two thermal-responsive devices responsive in different degrees to current traversing the circuit, of contact members actuated by the movement of the said responsive devices, said responsive devices being adapted to so actuate the contact members that they are engaged simultaneously only when the current traversing the circuit has decreased to a predetermined value.

In testimony whereof, I have hereunto subscribed my name this 6th day of August, 1915.

MAX HARTENHEIM.
